UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,279,811.

Specification of Letters Patent. Patented Sept. 24, 1918.

Application filed December 8, 1916. Serial No. 135,764.

To all whom it may concern:

Be it known that I, SAMUEL B. WILLIAMS, Jr., a citizen of the United States, residing at Brooklyn, in the county of Kings and State of New York, have invented certain new and useful Improvements in Telephone-Exchange Systems, of which the following is a full, clear, concise, and exact description.

10 This invention relates to telephone exchange systems wherein a calling line is automatically associated with a connecting circuit by a non-numerical switch upon the removal of the receiver at the substation of such line, and particularly to such a system wherein, during light load hours, as, for example, during the night, all incoming calls are automatically concentrated upon a particular operator's position, the other positions being made artificially busy. It frequently happens that all the connecting circuits terminating at such positions, apportioned to a particular group of lines, are busy when another call is initiated in such 25 group. This call therefore has to wait until one of the connecting circuits becomes idle.

It is the object of this invention to provide an improved arrangement for systems of this type, wherein, in the event of all the connecting circuits of a particular line group becoming busy, the initiation of a call in such group will automatically remove the artificial busy condition of the other positions, whereupon one of the connecting circuits thereof will automatically take the call, which the night operator can then attend to.

40 In accordance with this invention, the initiation of a call sets in operation an electro-responsive timing device, and if the line initiating such call is not extended to a connecting circuit within a predetermined interval, such device renders the busy connecting circuits at the other positions accessible to the calling line, whereupon the line is automatically extended to one of such connecting circuits.

More specifically, a train of slow relays is employed which operate successively upon the energization of any line relay, and each relay is maintained energized in a circuit dependent upon the preceding relay. The last one of these slow relays operates a relay which locks itself in a circuit closed as long as the line relay is energized, and connects

a relay, which, when operated, renders the connecting circuits non-busy, to the back contact of the last slow relay and opens the circuit of the first slow relay. This relay, after an interval, allows its armature to retract thus opening the circuit of the succeeding slow relay which, in turn, after an interval, retracts its armature, opening the circuit of the next slow relay, the retraction of the armature of the last slow relay completing the circuit of the relay which restores the non-busy condition of the other positions, whereupon the calling line is automatically extended to one of such connecting circuits.

If, as is usually the case, the calling line is extended and the line relay rendered inert before the last slow relay retracts its armature, the locking circuit referred to is opened at the time the last slow relay deenergizes, and consequently the circuit of the relay which removes the busy condition of the connecting circuits is not closed.

The invention will be more readily understood when described with reference to the accompanying drawings, wherein Figure 1 indicates a calling line and the answering end of a connecting circuit, and Fig. 2 a called line and the calling end of the connecting circuit.

Upon the removal of the receiver at substation A, the line relay LR is energized over the calling line circuit. This relay, in attracting its left armature, grounds the multiple 101 of the calling line, and, in attracting its right armature, energizes relays 102, 103, common to the group of lines containing substation A. Relay 102, in attracting its right armature, grounds commutator multiple segment 104 of the group to which substation A belongs to render the group calling. Relay 103, in attracting its right armature, closes the following circuit to energize the escape magnet 106 of the line-finder side switch; free pole of battery, primary stopping magnet PM, escape magnet 100 106, side-switch arm 1, armature and back contact of magnet PM, armature and back contact of magnet SM, conductor 108, right armature and front contact of relay 103, conductor 109, conductor 200, outer armature and back contact of relay 201, conductor 202, armature and back contact of the calling supervisory relay 203, conductors 290, 291,

normally closed contact 292 of key *k* to ground. Magnet PM does not energize in this circuit. The escape magnet 106 is constructed to release the side switch from position to position upon its energization.

In position 2, arm 1 connects magnet PM over the back contacts of magnets PM, SM, to grounded conductor 108, whereupon the finder brush shaft 119 is given a primary movement by the operation of such magnet PM. In position 2, arm 2 closes the following circuit for relay TR: free pole of battery, magnet SM, arm 2, left winding of relay TR, armature and back contact of magnet SM to grounded conductor 108. This relay is adapted to attract its armature upon the closure of this circuit, but magnet SM remains inert. Relay TR, at its inner armature and front contact, connects the escape magnet over arm 3 and its second contact to the commutator brush 115. When brush 115 encounters the calling commutator segment 104, now grounded, escape magnet 106 energizes over the following circuit, and releases the side switch into position 3: free pole of battery, magnets PM, 106, conductors 117, 118, armature and front contact of relay TR, arm 3 and its second contact, conductors 120, 130, commutator brush 115, segment 104, now grounded at the armature and front contact of relay 102. Arm 1, in moving out of position 2, opens the circuit of magnet PM, thus stopping the primary movement of the finder brush shaft 119 with a set of brushes 110, 111, 112 in operative relation to multiples of the calling line group containing those of the calling line 101, 113 and 114.

In position 3, relay TR is energized over the following circuit: free pole of battery, magnets PM, 106, arm 2 and its third contact, left winding of relay TR, armature and back contact of magnet SM, grounded conductor 108. Magnets PM and 106 do not energize in this circuit. Relay TR, at its outer armature and front contact, closes the following circuit to operate the secondary stepping magnet SM to drive the brushes 110, 111 and 112 over the multiples containing those of the calling line 101, 113 and 114: free pole of battery, magnet SM, outer armature and front contact of relay TR, arm 1 and its third contact, armature and back contact of magnet PM, armature and back contact of magnet SM, to grounded conductor 108. The magnet SM interrupts the circuit traced through the left winding of relay TR as well as its own circuit, and this relay therefore vibrates, except when the brush 112 engages the test multiples 114 of busy lines, when it is held energized from battery on such terminals, brush 112, conductor 120, arm 3 and its third contact, right winding of relay TR, to ground, as will be more particularly described hereinafter.

When, however, the brush 112 reaches the calling line multiple 114, relay TR becomes deenergized, and, since ground is present on multiple 101 of the calling line, the following circuit is closed for escape magnet 106: 70 free pole of battery, magnets PM, 106, conductors 117, 118, inner armature and back contact of relay TR, arm 5 and its third contact, brush 110, terminal 101, to ground at the left armature and front contact of relay 75 LR. Magnet 106 upon its energization, releases the side switch into position 4. Thus, the finder brushes 110, 111, 112 remain on the calling line multiples 101, 113, 114. In position 4, the calling line is extended by 80 arms 4 and 5 to the conductors 121, 122, whereupon the calling supervisory relay 203 is energized over the calling line circuit.

In position 4, arm 3 of the finder side switch closes the following circuit to energize the cut-off relay CO of the calling line: free pole of battery, resistance 206, conductors 214, 125, arm 3 and its fourth contact, conductor 120, brush 112, terminal 114, cut-off relay CO to ground. This potential applied to multiples 114 by brush 112, holds relay TR of a moving finder energized over its right winding as the brush 112 of such finder wipes over such multiples, as hereinbefore described. Relay CO, in attracting 95 its armatures, deenergizes the line relay LR, which, in retracting its left armature, removes the calling condition from the multiples 101 of the calling line, and, in retracting its right armature, deenergizes 100 group relays 102, 103. Relay 102, in retracting its right armature, removes the calling condition from the commutator multiples 104 of this group.

Relay 203, in attracting its armature, operates a relay 204, which lights the calling lamp 240, whereupon the operator depresses listening key K', which connects her head-set 238 in circuit with the calling line, assuming plugs 270 and 271 to be inserted in 105 jacks 272, 273 respectively. The actuation of the listening key K' closes the following circuit for a relay 205: free pole of battery, resistance 206, contact 297 of key K', conductor 208, relays 205, 209, to ground. Relay 209 is marginal and does not operate in this circuit. Relay 205, by attracting its armature, closes one break in the circuit of winding 210 of the operator's head-set. 115

The operator now asks the calling party the number of the line wanted. The talking circuit between the operator and the calling party will not be traced in detail since it is readily apparent from the drawing. The operator now tests the line in the well-known manner, by touching the tip of calling plug 211 to the sleeve of the jack 212. If the line is busy, relay 209 energizes and in attracting its armature produces a click 120 in the operator's telephone in the well-known 125 manner. The operator then asks the calling party the number of the line wanted. The talking circuit between the operator and the calling party will not be traced in detail since it is readily apparent from the drawing. The operator now tests the line in the well-known manner, by touching the tip of calling plug 211 to the sleeve of the jack 212. If the line is busy, relay 209 energizes and in attracting its armature produces a click 130 in the operator's telephone in the well-known

manner. In the absence of a click in her telephone, the operator inserts the plug into the jack, whereupon sleeve relay 213 is energized in series with the cut-off relay of the 5 called line. Relay 213, in attracting its armature 251, connects conductor 231 to the tip of the plug, and in attracting its armature 252, energizes relay 201 and lights lamp 233. In attracting its armature 253, relay 213 de- 10 energizes relay 204, extinguishing the lamp 240. Relay 201, in attracting its armature, closes the following circuit for a relay 226 adapted to apply ringing current to the called line: free pole of battery, inner armature 15 and front contact of relay 201, conductor 227, relay 226, armature and back contact of relay 228, and armature and back contact of relay 229 to ground. Relay 226, in attracting its armatures, connects current 20 from the generator 274 to the called line. When the called party removes his receiver, relay 229 attracts its armature, thus removing the shunt around relay 228, which there- 25 upon energizes. Relay 228, in attracting its armature, locks itself to ground and shunts out relay 226, which, in retracting its armatures, opens the ringing circuit and reconnects the talking conductors to the tip and ring of the calling plug 211. The called 30 supervisory relay 241 is thereupon energized over the called line, and, in attracting its armature, extinguishes supervisory lamp 233. The parties may now converse.

Upon the termination of the conversation 35 and the replacement of the receiver by the calling party relay 203 becomes deenergized and closes the following circuit for relay 204: ground, contact 292 of key K, conductors 291, 290, armature and back contact of relay 203, conductor 202, outer armature and front contact of relay 201, conductors 290', 291, relay 204, free pole of battery. Relay 204, in operating, lights the supervisory lamp 240.

45 When the called party hangs up his receiver, relay 241 falls back, closing the circuit of lamp 233. The operator thereupon withdraws plug 211 from jack 212, which results in relay 213 becoming deenergized. 50 Relay 213, in retracting its upper armature, deenergizes relay 201, which opens the locking circuit of relay 228 at its inner armature, and at its outer armature closes the release circuit for the finder as follows: ground, contact 292 of key K, conductors 291, 290, armature and back contact of calling supervisory relay 203, conductor 202, outer armature and back contact of relay 201, conductor 200, conductor 109, right armature and back 55 contact of relay 103, primary off-normal contact PON, release magnet RM, free pole of battery. Magnet RM, in attracting its left armature, locks itself over the off-normal contact to ground. When the finder brush shaft 60 65 119 is completely restored, this off-

normal contact opens and unlocks the release magnet. The finder in releasing opens the circuit of cut-off relay CO.

Going back to that point in the operation where the removal of the receiver starts a 70 finder seeking the calling line, it will be remembered that the initiation of such call energized group relay 103, which, in attracting its right armature, extended the conductor 109 grounded at the normal contact 75 of key K, to the escape magnet 106 to initiate the primary movement of the finder brush shaft. In parallel with magnet 106, a quick acting relay 131 is energized when relay 103 operates, this circuit being as fol- 80 lows: free pole of battery, relay 131, spring 132, conductors 133, 117, arm 1 and its first contact, armatures and back contacts of magnets PM, SM, conductor 108, right armature and front contact of relay 103, conductors 85 109, 200, outer armature and back contact of relay 201, conductor 202, armature and back contact of relay 203, conductors 290, 291 to ground at the normal contact 292 of key K. Relay 131, by attracting its right 90 armature, locks itself directly to grounded conductor 108, and by attracting its left armature, opens the connection between the grounded left-hand armature of relay 102 and the out-starter wire 134, leading to the 95 escape magnet 106 of the next finder. If the finder shown in Fig. 1 had been busy, relay 203 would have been energized, and consequently the circuit for relay 131 just traced would not have been completed, and 100 this relay failing to energize, the grounded left-hand armature of relay 102 would be connected over the left armature of relay 103 to the out-starter wire 134, leading to the escape magnet 106 of the next finder, to set 105 the finder shaft in motion seeking the calling line. Thus, the starter wire is normally extended to the next idle finder. Assuming the finder shown in Fig. 1 to be the 110 next idle finder, the circuit may be continued as follows: in-starter wire 135, left armature and back contact of relay 102, relay 103, conductor 136, right armature and back contact of magnet RM, resistance 137, free pole of battery. Relay 103, in at- 115 tracting its left armature, connects the in and out-starter wires 135, 134 together, and in attracting its right armature, energizes the escape magnet 106 of such finder as de- 120 scribed, which, upon energizing, releases the side switch into position 2 to initiate the primary movement of the finder brush shaft. From this point on the operations are the same as those already traced.

The particular feature of the present cir- 125 cuit arrangement claimed herein will now be described. When the light load hours approach, all the operators except one leave their positions, throwing the keys K to remove ground from conductors 291 of all of 130

their connecting circuits. Each group of lines has a number of connecting circuits terminating at the night position.

Now, if all the connecting circuits terminating at the night operator's position serving any particular line group are taken for use and another call is initiated in such group, the artificial busy condition of the other positions is automatically removed 10 and one of the finders thereof finds the calling line and lights the corresponding lamp 240, whereupon the night operator takes care of such call.

In detail, this operation is as follows: 15 When a call is initiated, and relay 102 operates, the attraction of the outer left armature of such closes the following circuit for the first relay *a* of a train of slow relays *a*, *b*, and *c*: grounded left armature 20 of relay 102 and its front contact, conductor 175, left armature and back contact of relay *d*, conductor 176, slow relay *a* to free pole of battery. Relay *a* in attracting its armature energizes relay *b* over the following 25 circuit: free pole of battery, slow relay *b*, armature and spring of relay *a*, conductor 177, to grounded conductor 175. Relay *b*, in attracting its armature, closes the following circuit for the relay *c*: free pole of battery, slow relay *c*, armature and spring of 30 relay *b*, conductor 177 to grounded conductor 175. Relay *c*, in attracting its armature, closes the following circuit for relay *d*: free pole of battery, relay *d*, armature 35 and spring of relay *c*, conductor 177 to grounded conductor 175. Relay *d* in attracting its left armature opens the circuit of relay *a* and locks itself to grounded conductor 175. Relays *a*, *b*, and *c* thereupon 40 fall back in succession. When relay *c* retracts its armature, the following circuit is closed for the relay *e*: free pole of battery, relay *e*, conductor 178, right armature and front contact of relay *d*, armature and back 45 contact of relay *e*, conductor 177 to grounded conductor 175.

Relay *e* in attracting its armatures again connects ground to the conductors 179. The grounding of these conductors renders the 50 connecting circuits of the other positions non-busy. The circuit for operating the escape magnet 106 of a finder to pass its side switch into position 2 to initiate the primary movement of the brush shaft is now 55 traced as follows: free pole of battery, magnets PM and 106, arm 1 and its first contact, armatures and back contacts of magnets PM and SM, conductor 108, right armature and front contact of relay 103, 60 conductors 109, 200, outer armature and back contact of relay 201, conductor 202, armature and back contact of relay 203, conductor 290, conductor 179, to ground at the armature and front contact of relay *e*.

65 When the calling line is found and the

cut-off relay CO thereof operated to de-energize the line relay LR, group relays 102 and 103 become inert. The retraction of the outer left armature of relay 102 unlocks relay *d* which, in retracting its right armature, deenergizes relay *e*. Relay *e* in retracting its armature again removes ground from the conductors 179, thus rendering the positions to which such conductors belong again artificially busy. While the string of 75 the slow relays *a*, *b* and *c* are started in operation by the initiation of every call, the line initiating such call is generally reached by the finder and the cut-off relay thereof operated before the last slow relay *c* retracts 80 its armature to operate and lock up relay *d*. It is only when a finder is not available that the relay *d* is locked up to operate relay *e*.

What is claimed is:

1. In a telephone exchange system, the 85 combination with telephone lines, connecting circuits, automatic non-numerical switches for extending calling lines to said connecting circuits, and means for rendering certain of said non-numerical switches artificially busy, of a timing device set in operation by the initiation of a call, means automatically actuated when the calling line is extended to disable said timing device, and means actuated by said timing device if not disabled 90 within a predetermined interval for removing the artificial busy condition of said non-numerical switches.

2. In a telephone exchange system, the 100 combination with telephone lines, connecting circuits, automatic non-numerical switches for extending calling lines to said connecting circuits, and means for rendering certain of said non-numerical switches artificially busy, of a timing device including a train of slow 105 relays, means for energizing said relays successively upon the initiation of a call, means actuated by the operation of the last slow relay for deenergizing said relays successively, and means actuated by the deenergization of the last slow relay for removing the artificial busy condition of said non-numerical switches.

3. In a telephone exchange system, the 115 combination with telephone lines, connecting circuits terminating in automatic finder switches to which said lines are multipled, operator's positions at which said connecting circuits terminate, means for causing one of said finders automatically to connect with a calling line, and means for rendering all of the finders busy except those of the connecting circuits terminating at a given position, of a timing device set in operation by the initiation of a call, means automatically actuated when the calling line is extended to disable said timing device, and means actuated by said timing device if not disabled within a predetermined interval for removing the 120 artificial busy condition of said finders.

4. In a telephone exchange system, the combination with telephone lines divided into groups, a group of connecting circuits terminating in automatic finder switches to 5 which said lines are multiplied in groups, operators' positions among which said connecting circuits are distributed in such a manner that some of the connecting circuits serving each group appear at each position, 10 means for causing one of said finders to connect with a calling line upon the initiation of a call therein, and means for rendering all of the finders busy except those of the connecting circuits terminating at a given 15 position, of a timing device set in operation by the initiation of a call, means automatically actuated when the calling line is extended to disable said timing device, and means actuated by said timing device if not disabled 20 in a predetermined interval for removing the artificial busy condition of said finders.
5. In a telephone exchange system, the combination with telephone lines, line and cut-off relays LR and CO therefor, connecting circuits, automatic non-numerical switches for extending calling lines to said 25

connecting circuits and for operating the relays CO thereof, and means for rendering certain of said non-numerical switches artificially busy, of a timing device including a train of slow relays (a, b, c) and a relay 120, said relay 120 being energized upon the initiation of a call and causing the successive energization of said slow relays, a relay e for 30 removing the artificial busy condition of said switches, a relay d operated by the last slow relay c to connect said relay e to the back contact of the last slow relay c and to open the circuit of the first slow relay a , a locking circuit for relay d closed upon its energization and controlled by the relay 120, whereby the retraction of the armature of the last slow relay c before a predetermined 35 interval completes the circuit of the relay e which restores the non-busy condition of the connecting circuits, while the retraction of such armature after the operation of the cut-off relay of the calling line is without effect on relay e . 40

In witness whereof I hereunto subscribe my name this 7th day of December, A. D. 1916.

SAMUEL B. WILLIAMS, JR.
